UNITED STATES PATENT OFFICE.

JOSHUA TWING BROOKS, OF EDGEWORTH, AND EDMUND A. SKOWRON, OF PITTSBURGH, PENNSYLVANIA, SAID SKOWRON ASSIGNOR TO SAID BROOKS.

RAIL ANCHOR.

Application filed March 7, 1928. Serial No. 259,653.

The invention relates to rail anchors.

The objects of the invention are to provide a two-piece anchor for attachment to railway rails, one part being adapted to give a strongly gripping jaw action on one side of the rail, the other part being adapted to hold the jaw in engaged position under spring pressure, to grip the rail transversely with shackle effect, and to have a biting action on the upper and lower faces of the rail base on canting of the anchor due to abutment with a tie. Another object is to provide a rail anchor that will take and maintain a secure jaw grip even though there be some variation in width or thickness of the edge of the rail base flange. Another object is to provide a jaw member and spring-retaining device therefor in which the jaw in being driven laterally at one side to operative position exerts tension on the holding member, which tension is partially relieved by driving the jaw over center to final position of the movable edge of the jaw member, resulting in a cooperative arrangement requiring an extension of the spring member in order to release the jaw.

Referring to the drawings, Fig. 1 is a plan view of the anchor as applied to the base of a rail, the rail being merely indicated, the undistorted condition of the anchor being indicated by dotted lines; Fig. 2 is a vertical section through a portion of the rail showing a side elevation of the anchor as applied thereto; and Fig. 3 is a view of the anchor in course of application or removal, the jaw piece being in alignment or "on centre" with respect to the spring piece, and the positions of the jaw before and after locking being indicated.

In Fig. 2 there is illustrated a standard rail R consisting of a web 1, and base flanges 2 and 3, the head of the rail being removed. The anchor consists of a spring piece S adapted to extend across the rail, and a jaw piece J adapted to grip one side of the rail base, and to be retained in position thereon by the spring piece. Both pieces are preferably made by punching and pressing from a plate of high grade steel of uniform thickness.

The spring piece has a vertical hook H formed at one end, comprising a terminal overlapping portion 5, a vertical connecting portion 6, extending from the main body

portion 7. A recess 8 is formed between the portions 5, 6, and 7, large enough to permit the hook to be readily slipped over and turned about the edge of the rail. The body portion 7 has an intermediate rearward bend 10, beyond which the spring piece is straightened out to form a tie-abutting portion 11, beyond which the other end is bent in a rearwardly sloping portion 12 with a terminal lateral substantially vertical hook 13. By portion 12 the hook 13 is offset away from the plane of portion 11. This terminal hook portion 13 is positioned a material distance away from the rail and from the tie. The spring piece may be easily hooked over the edge of the rail at the end H, and then the other end brought upward until the intermediate portion 11 lies against the under face of the rail. The transverse body portion of the spring is widened at the laterally hooked end, having an upwardly extending portion 14. This has its inner corner cut off at 15, to save weight and to permit the inner corner to clear the rail base edge in application. The top of the spring at the bend 10 is slightly cut away at 16 so that that portion of the spring will not contact with the rail. This is shown in Fig. 2. Between the cut away portion 16 and the portion 8 a portion 17 abuts the rail and forms a jaw grip with the under side of portion 5 when the anchor is canted.

The jaw piece J is formed of a forging or plate stamping. The outer edge 20 of the jaw member is rounded off slightly so as to form a smooth seating contact inside the hook 13. The hook 13 is inclined slightly inward toward the rail from bottom to top, and the outer edge 20 of the jaw piece is similarly inclined from the vertical when the jaw is in engagement with the rail. This helps to lock the spring piece against movement downward away from the rail at the end 13 thereof. The opposite inner edge 21 of the jaw member has formed therein a tapered notch with an upper face 22 and lower face 23 having the same angular relation as the upper and lower faces of one side of the rail base. The two faces 22 and 23 terminate in an enlarged rounded opening 24, adapted to form a clearance around the side face and corners of the rail base. This is for the purpose of permitting the jaw formed by the faces 22 and 23 to move inward on the

rail base until they seat thereon, without contact with the side face of the rail.

The mode of attachment and general functioning of this anchor is as follows:

- 5 With the rail R in position upon the tie T, as shown in Figs. 1 and 3, the spring piece S is inserted under the rail, and the hook end H thereof engaged with the side 3 of the rail base. The other end 13 is then
10 brought upward until the upper face of the spring member contacts with the under face of the rail, as shown in Fig. 2. The jaw member J is then placed in the hook 13, the outer edge 20 of the jaw member
15 seating inside the hook. The inner edge 21 of the jaw member is rotated about the portion 20 as an axis. The faces 22 and 23 of the jaw will ride upon the rail base 2 and as the jaw turns on axis 20, being fulcrumed
20 in hook 13, it will reach a position where the jaw faces 22 and 23 both engage the rail base, the edge 20 being at the same time in engagement with the inner face of the hook 13 of the spring member. This will be
25 approximately the position A shown in dotted lines in Fig. 3.

Thereafter the inner portions of the jaw member above or below the rail are struck with a tamping pick or any suitable tool.

- 30 This drives the inner edge 21 of the jaw member from the position A of the dotted lines towards the position C in full lines in Fig. 1. Since the edges of the jaw are in engagement with the rail base in the
35 dotted line position A of Fig. 3, in order for the inner edge of the jaw piece J to move to full line position B of Fig. 3, where it is "on centre," there must be a give somewhere in the metal parts involved. This is effected by straightening in part of curved portions 10 and 12 of the spring member.

- 40 When the force of the blows is exerted on the jaw piece to rotate edge 21 about edge 20 the jaw faces 22 and 23 will ride on the inclined rail base, thereby gripping the base and tending simultaneously to separate the jaw faces, by compression of the rail and tension of the metal of the jaw piece, respectively. This will result in a
45 very tight bite of the jaw on the upper and lower faces of the rail base. At the same time due to the inclined-plane effect of the rail base and gripping jaw, there will be a backing off of the jaw from the rail base
50 as the inner edge 21 of the jaw piece is driven around the edge 20, and consequently over the rail base. The outer edge of the jaw member will necessarily move further away from the rail as it rotates about axis 20, i. e., as the member J moves from position A to position B, where it is on centre, as shown in Fig. 3. This results in a tensioning effect on the spring piece S, which gives, due to straightening out of the bends
55 of the portions 10 and 12. This permits the

jaw to be driven from the dotted line position A of Fig. 3 to the full line position B of Fig. 3.

Maximum distortion of the spring piece will be required at the position B intermediate the two positions A and C illustrated in Fig. 3. The full line on centre position B of Fig. 3 will be at the point when the median plane of the jaw member J is normal to the rail axis. After the jaw is driven past that on centre position B towards the full line normal operating position C of Fig. 1, the tension on the spring piece will be only partially relieved. In other words the inner edge of the jaw piece will be driven past centre but not as far past centre as its initial position A. The spring piece therefore draws the hook 13 inward as the edge 21 of the jaw member advances on the rail past centre, to the position C shown in full lines in Fig. 1. The bend 12 is so proportioned that when jaw member J is seated therein as shown in Fig. 1, position C, i. e. with both ends of the jaw piece bearing against the spring piece, the inner edge of the jaw will not have traveled far enough to entirely relieve tension of the spring. Hence the latter exerts a constant pressure inward on the jaw member.

55 After the jaw has been driven laterally to position C, a blow is preferably given the outer edge of hook 13 in the line of the jaw piece, to drive the latter on the rail more firmly. The final result is that the jaw firmly engages the rail base with a driven grip, and is held in that position under a strong tension due to distortion and constant grip of the spring piece S.

100 The dotted outline of the spring member in Fig. 3 is intended to illustrate diagrammatically the position of the spring piece before the jaw member is driven at all, the full lines showing the extent of distortions of the spring. The dotted line in Fig. 1 indicates the position the spring would occupy if the jaw were not inserted therein. The full lines of Fig. 3 compared with the dotted line thereof show the maximum distortion of the spring necessary to drive the jaw over centre to locked position.

105 In order to remove the anchor it is necessary to drive the inner edge 21 of the member J rearwardly past centre, i. e. past the position B. That again requires extension of the spring piece. Consequently the jaw is not liable to accidental release.

110 The portion 11 of the spring piece bears against the tie T, and as the rail tends to move forward through the anchor toward the tie, in the direction indicated by the arrow, three effects will be produced. In the first place this tendency of the rail to move will drive the jaw member inward against the spring member and the latter against the tie. Thus creeping of the rail constantly re- 115

tains the jaw in locked position. In the second place, abutment of the tie against the under-swung portion 11 of the spring piece will cant that portion of the anchor away from the tie. This results in a biting grip of the forward edge of portion 5, and the rear edge of the contacting portion 17 on the flange 3 of the rail base. It will also tend to give an edge biting effect of the jaw member J on the upper and lower faces of the rail. At the same time, since the portion 11 of the spring piece bears against the tie, whereas the portion 7 does not, there will be a tendency to move the hook end H of the spring piece towards the tie. This will produce a shackle effect, increasing the transverse grip on the rail between the portion 6 of the spring piece on one side and the jaw J on the rail at the other side. Consequently the anchor will grip in three separate and distinct ways, each of which will be accentuated by the tendency of the rail to creep therethrough.

The anchor may be economically manufactured from plate metal by simple die operations. It does not require heavy parts. Although under constant spring tension there is no danger of accidental loosening or flying off. Many advantages will be apparent to those familiar with the art.

We claim:

1. A two-piece rail anchor comprising a plate spring member having a vertical hook at one end adapted to engage one edge of the rail base and a lateral hook at the other end, a jaw member adapted to seat in said lateral hook to preliminarily engages the edge of the rail base and then to be driven into locked engagement with the rail by distorting the first member.

2. A two-piece rail anchor comprising a substantially rigid jaw member adapted to engage one edge of a rail base, and a plate spring member having a lateral hook adapted to fulcrum the jaw member during a horizontal swinging of the rail-engaging edge thereof, and a vertical hook at the other end adapted to engage the other edge of the rail base, whereby to retain the jaw in rail-engaging position under constant spring pressure.

3. A two-piece rail anchor comprising a substantially rigid jaw member adapted to engage one edge of the rail base, and a spring member adapted to fulcrum the jaw member, to hook over the other edge of the rail base and to retain the jaw member in position under spring pressure, said spring member being formed of a plate and adapted to form retaining abutment with a tie below the rail.

4. A two-piece rail anchor comprising a plate spring member having a vertical hook at one end adapted to engage one edge of the rail base, and an offset lateral hook at

the other end, a substantially rigid jaw member adapted to seat in said lateral hook and to engage the edge of the rail base upon swinging horizontally in said hook as a fulcrum, and to be driven into locked position 70 against tension of the spring member.

5. A two-piece rail anchor comprising a jaw member adapted to grip one edge of the rail base, and a spring member having a lateral hook at one end adapted to fulcrum the 75 jaw member and a hook at the other end adapted to engage the other edge of the rail base, the spring having an intermediate lateral bend adapted to permit extension of the spring member to permit the jaw member to be driven against spring pressure to operative position on the rail.

6. A two-piece rail anchor comprising a plate member having a vertical hook at one end adapted to engage one edge of the rail 85 base and a lateral hook at the other end, a jaw member adapted to seat in said lateral hook and to engage the edge of the rail base and to be driven laterally into locked position by distorting the spring member, the 90 spring member having a lateral bend permitting distortion to seat the jaw member.

7. A rail anchor comprising a substantially rigid jaw member adapted to be driven into operative gripping engagement with the 95 flange of the rail by a horizontal swinging movement, and a spring member adapted to be hooked over the edge of the rail flange at the opposite side and to retain the outer edge of the jaw member in a vertical fulcrumming hook and to lock the jaw member 100 in rail-engaging position under constant pressure of the spring when the jaw member is driven past centre in the spring member.

8. A rail anchor comprising a jaw member adapted to be driven into operative engagement with the flange of a rail by a horizontal swinging movement, and a spring member adapted to be hooked over the edge of the rail flange at the opposite side, to 110 bear against the outer edge of the jaw member to fulcrum it in its movement to locked position, and to lock the jaw member in rail-engaging position under constant pressure of the spring member.

9. A rail anchor comprising a jaw member adapted to be driven into operative gripping engagement with the flange of the rail, a spring retaining member adapted to be hooked over the edge of the flange at the 120 opposite side of the rail and having a vertical hook at the other end adapted to form a fulcrum for the outer edge of the jaw member, the inner edge of the jaw member being adapted to be driven into operative 125 position by movement along the rail edge after its outer edge is seated in said retaining hook, the spring member being distorted by the driving of the jaw member to locking position, whereby to retain the jaw 130

member in locked position under constant spring tension.

10. A rail anchor comprising a jaw member adapted to be driven into operative gripping engagement with the flange of the rail, a spring retaining member adapted to be hooked over the edge of the flange at the opposite side of the rail and having a vertical hook at the other end adapted to form a fulcrum for the outer edge of the jaw member, the jaw member being adapted to be driven into operative position by swinging horizontally after it is seated in said retaining hook, the spring member being distorted by the driving of the jaw member to locking position, whereby to retain the jaw member in locked position under constant spring pressure.

11. A rail anchor comprising a spring member adapted to extend underneath the rail base and having hooks at its opposite ends, one of said hooks being adapted to extend around the edge of the rail base, and the other hook being vertically disposed and spaced away from the edge of the rail, and a jaw member adapted to have its outer edge seated and fulcrumed in said vertical hook of the spring member and to be driven into locking position with the rail against pressure of the spring member.

12. A rail anchor comprising a spring member adapted to extend underneath the rail base and having a vertical hook at one end adapted to engage one edge of the rail base, a lateral hook at the other end spaced away from the rail base, and a jaw member adapted to be fulcrumed in the lateral hook and to be driven into locking engagement with the rail by a swinging movement overcoming resistance of the spring member.

13. A rail anchor comprising a spring member adapted to extend underneath the rail base and having hooks at its opposite ends, one of said hooks being adapted to extend around the edge of the rail base, and the other hook being vertically disposed and spaced away from the edge of the rail, and a jaw member adapted to have its outer edge seated in said vertical hook of the spring member and to be driven into locking position with the rail against pressure of the spring member, the jaw member being adapted to extend the spring member as its inner edge is driven toward the spring member, the inner edge of the jaw member lying against the spring member in final position of the jaw member.

14. A rail anchor comprising a spring member adapted to extend underneath the rail base and having a hook at one end adapted to engage one edge of the rail base, a lateral hook at the other end spaced away from the rail base, and a jaw member adapted to be fulcrumed in the lateral hook and to be driven into locking engagement with

the rail by overcoming resistance of the spring member, and to be retained in operative position under spring pressure.

15. A two-piece rail anchor comprising a substantially rigid plate having a straight outer edge, the opposite inner edge having a tapered jaw formed therein and adapted to engage the upper and lower faces of one edge of a rail base, a spring member formed of a plate of resilient metal having a vertical hook at one end adapted to engage one edge of a rail base, an intermediate lateral bend and a lateral hook at the other end, the lateral hook being adapted to seat the outer edge of the jaw member, intermediate portions of the spring member being adapted to contact with the under side of the rail and to abut a tie beneath the rail, the end of the spring having the lateral hook being bent rearwardly, the jaw member being of such width that when the spring member is applied to a rail and then the jaw member seated in the lateral hook and its jaw brought to contact with the rail the jaw member is positioned at an angle to the rail.

16. A two-piece rail anchor comprising a jaw member and a spring member, the jaw member having a notch for engaging the upper and lower faces of a rail base flange and a straight outer edge, the spring member having an upright hook at one end adapted to engage the rail base, an intermediate bend adapted to permit extension of the spring member, and a terminal lateral hook at the other end adapted to receive and fulcrum the outer edge of the jaw member in a swinging movement of the notched edge thereof, the inner face of said lateral hook and the outer edge of the jaw member being inclined inward from bottom to top thereof.

17. A two-piece rail anchor comprising a jaw member and a spring member, the jaw member having a notch for engaging the upper and lower faces of a rail base flange and a straight outer edge, the spring member having an upright hook at one end adapted to engage the rail base, a terminal lateral hook at the other end adapted to receive and fulcrum the outer edge of the jaw member in a swinging movement of the notched edge thereof, the jaw member being adapted to be driven past centre with reference to said fulcruming hook and to lie against the spring and under compression against the rail thereby.

18. A two-piece rail anchor comprising a jaw member and a spring member, the jaw member having a notch for engaging the upper and lower faces of the rail base flange and a straight outer edge, the spring member having an upright hook at one end adapted to engage a rail base, an intermediate bend adapted to permit extension of the spring member, and a terminal lateral hook at the other end adapted to receive

and fulcrum the outer edge of the jaw member in a swinging movement of the notched edge thereof, the top of said intermediate bend being lowered so as not to contact with the rail.

19. A two-piece rail anchor comprising a jaw member and a spring member, the jaw member having a notch for engaging the upper and lower faces of the rail base flange and a straight outer edge, the spring member having an upright hook at one end adapted to engage a rail base, an intermediate bend adapted to permit extension of

the spring member, and a terminal lateral hook at the other end adapted to receive and 15 fulcrum the outer edge of the jaw member in a swinging movement of the notched edge thereof, the said upright hook of the spring member having inner faces adapted to grip the tie on canting of the spring relative to a 20 vertical plane therethrough.

In testimony whereof, we hereunto sign our names.
